UNITED STATES PATENT OFFICE

INGVALD O. PEDERSEN AND ERIK G. STAHL, OF PITTSBURGH, PENNSYLVANIA, ASSIGNORS TO LIBBEY-OWENS-FORD GLASS COMPANY, OF TOLEDO, OHIO; A CORPORATION OF OHIO

SURFACING MACHINE

Application filed July 14, 1927. Serial No. 205,665.

This invention relates to improvements in surfacing machines and particularly to grinding machines for treating sheets of material such as glass and the like.

ployed to designate like parts throughout the same,

Fig. 1 is an elevation of an improved grinding machine constructed in accordance with the present invention.

55

Fig. 2 is a transverse vertical section showing the connection between the grinding head and its spindle,

60

Fig. 3 is a transverse section taken substantially on line 3—3 of Fig. 2; and

65

Fig. 4 is a detail section of the means for raising and lowering the grinding machine.

Referring to the drawings, 5 designates in its entirety the improved grinding machine which embodies a stationary casing 6 in which is journaled the vertical runner spindle 7 driven from a suitable motor or the like through the intermediary of suitable gearing located in the upper enlarged end 8 of casing 6. This driving means is set forth in detail in our copending application filed June 7, 1927, Serial No. 201,663.

70

The numeral 10 indicates the main runner casting or grinder head upon the lower face of which is the usual planking 11 to which the runner or grinding block 12 is secured. The runner block 12 and planking 11 have their centers cut out to form a cavity 13, this cavity being covered by a plate 14 integral with the casting 10 and provided with a plurality of openings 15 through which a mixture of abrasive and water is supplied as is hereinafter explained. Integral with the plate 14 is an upstanding annular housing 16 defining a socket or recess 17 at the central portion of the casting 10, said socket being adapted for receiving the connection between the spindle 7 and grinder head. Bolted or otherwise suitably secured to the top of the housing 16 and covering a portion of the socket or recess 17 is a removable cover plate 18 formed at its inner edge with an upstanding annular flange 19.

85

The runner spindle 7 projects downwardly beyond the casing 6 as shown in Fig. 2 and has secured to its lower end 20 a hub 21. This hub 21 is vertically elongated and is fastened onto the spindle by means of a transverse key 22. Particular attention is called to the fact that this key is arranged exteriorly of the

90

100

5 The present invention is primarily adapted for use in connection with facing and smoothing plate glass in the so-called continuous process wherein the spindles of the grinder heads or runners are driven and the glass mounted on cars or tables is carried beneath the runners of a series of machines.

10 An important object of the invention is the provision of improved means for connecting the grinder head or runner of the machine to its spindle so as to permit a limited and variable amount of rocking movement of the said runner or grinder head.

Another object of the invention is to provide an improved connection between the grinder head of the machine and its spindle which will also permit a certain amount of bodily vertical movement of the grinder head relative to its spindle.

15 Another object of the invention is to provide such an improved connection which will not only permit a limited and variable amount of rocking movement of the grinder head but which will further serve as a driving means for imparting rotary movement thereto upon rotation of its spindle.

20 A further object of the invention is to provide such a novel connection wherein the means securing the grinder head to its spindle is readily accessible and may be easily and quickly removed or replaced without disturbing any of the other parts of the apparatus.

25 Still another object of the invention is to provide an improved connection of the above character including spring means adapted for yieldably supporting the grinder head only and which means will permit both rocking and vertical movement thereof relative to its spindle.

30 Other objects and advantages of the invention will become more apparent during the course of the following description when taken in connection with the accompanying drawings.

35 In the drawings forming a part of this application and wherein like numerals are em-

housing 16 and is readily accessible so that it may be removed or replaced without disturbing any of the other parts of the apparatus. To remove the grinder head from its spindle, it is simply necessary to first remove the key 22 after which the hub 21 and spindle 7 can be disengaged from one another.

Carried by the bottom of the casing 6 and surrounding the lower end 20 of spindle 7 is a packing box 23, the upper end of the hub 21 being formed with an annular recess 24 for catching any oil, etc. which might escape through the said packing box. Carried by the packing box arrangement 23 is a shield 15 or splash guard 25 enclosing the upper end of hub 21 to prevent any oil, etc., which might be in the recess 24, from splashing onto the glass being surfaced. The splash guard 25 also supports the main abrasive supply pipe 26. Secured to the hub 21 beneath the key 22 is a lower splash guard 27 which surrounds the annular upstanding flange 19 formed on the cover plate 18 whereby to prevent any abrasive from getting into the socket or recess 17 and thereby clogging up or otherwise interfering with the operation of the apparatus.

Formed integral with the main runner casting 10 and surrounding the housing 16 is an annular trough 28 for receiving the mixture of abrasive and water, which is to be used and which is supplied to the cavity 13 through the openings 15 in plate 14. This mixture of abrasive and water is initially fed into the trough 28 through the supply pipe 26 carried by the upper splash guard 25.

The lower end of the hub 21 is received within the socket 17 and is provided with three laterally projecting portions or arms 29, 30 and 31 upon each of which rests a compression spring 32, the upper end thereof bearing against a spring seat formed on the under face of the cover plate 18.

The hub 21 is also provided somewhat higher up with three laterally projecting driving arms 33, 34 and 35, these arms being arranged alternately with the spring supporting arms 29, 30 and 31 as shown in Fig. 3. Each of the driving arms 33, 34 and 35 is provided with a preferably bronze roll 36 which contacts with a preferably steel wear-plate 37 bolted to the inside of the housing 16. The rolls 36 serve to hold the runner or grinder head centrally located.

Projecting downwardly from the under-face of the cover plate 18 are six lugs 38, these lugs being arranged between the spring supporting and driving arms above described as clearly shown in Fig. 3. The lugs 38 rest against bosses 39 formed on the bottom of the grinder recess 17, said lugs being provided upon their faces which are adjacent the driving arms with preferably bronze wearing strips 40 with which the driving arms contact.

In the operation of the invention, and upon rotation of the runner spindle 7 and hub 21, the driving arms 33, 34 and 35 engaging the lugs 38 will serve to impart a rotary movement to the grinder head or runner. Since the driving arms are positioned between the lugs, the runner may be driven either in a clockwise or a counter-clockwise direction. The sheets of glass 41 to be surfaced are adapted to be supported upon the upper surfaces of a series of tables 42 mounted upon tracks 43, these tables serving to carry the glass sheets beneath the grinder heads or runners of a series of surfacing machines of the type set forth above. Due to the particular manner in which the runner is secured to its spindle, the said runner will be permitted a limited and variable amount of rocking movement. Also, the runner will further be permitted a certain amount of vertical movement as a whole relative to the spindle since there is a certain amount of clearance between the bottom of the hub 21 and plate 14. With the construction shown, the runner only is yieldably supported by the compression springs 32 so that when the whole weight of the runner is not resting on the glass, a part of its weight is taken up by these springs.

For the purpose of supporting the grinding machine, there is provided a hanger bracket 44, the upper end thereof resting upon and being secured to a horizontal I-beam 45 while the lower end bears against or is secured to a lower horizontal I-beam 46. The hanger bracket 44 is provided adjacent its upper end with spaced vertical cylinders or sleeves 47 and at its lower end with a plurality of bearings 48.

Carried at the upper end of the casing 6 is a pair of oppositely disposed plungers 49 which are slidably received within the cylinders or sleeves 47 while extending from the casing adjacent its lower end are a plurality of arms carrying vertical pins 50 slidably received within the bearings 48. The grinding machine may be readily removed from the hanger bracket by simply lifting the same until the plungers 49 and pins 50 are disengaged from the cylinders 47 and bearings 48 respectively.

In order to raise and lower the grinding machine, there is carried by each plunger 49 a depending adjusting screw 52 threaded through a worm gear 53 which is in constant mesh with a worm 54 mounted upon shaft 55. Upon rotation of the shaft 55, the worm gears 53 can be rotated in the desired direction to either raise or lower the grinding machine and the said shafts can be connected together, if desired, in such a manner that both plungers can be simultaneously raised or lowered so that both sides of the grinding machine may be raised or lowered an equal distance.

It is to be understood that the form of the

invention herewith shown and described is to be taken as the preferred embodiment of the same, and that various changes in the shape, size and arrangement of parts may be resorted to without departing from the spirit of the invention or the scope of the subjoined claims.

We claim:

1. In combination, a spindle rotatable about a fixed vertical axis, a runner positioned at the lower end of the spindle and having a socket therein, a hub secured to said spindle and received within said socket, and spring means carried by said hub within the socket and bearing against one wall thereof for yieldably supporting said runner.

2. In combination, a spindle rotatable about a fixed vertical axis, a runner positioned at the lower end of the spindle and having a socket therein, a hub secured to said spindle and received within said socket, and means arranged within the socket between said hub and runner and bearing against the same for yieldably supporting the latter.

3. In combination, a spindle rotatable about a fixed vertical axis, a runner positioned at the lower end of the spindle and having a socket therein, a hub secured to said spindle and received within said socket, said hub being provided with a plurality of laterally projecting portions arranged within the socket, and spring means carried upon said lateral portions also within said socket for yieldably supporting said runner.

4. In combination, a spindle rotatable about a fixed vertical axis, a runner positioned at the lower end of the spindle and having a socket therein, a hub secured to said spindle and received within said socket, spring means carried by said hub and arranged within said socket for yieldably supporting said runner, and a plurality of driving arms on said hub and also within said socket adapted for imparting a rotary movement to said runner upon rotation of said spindle.

5. In combination, a vertical spindle, a runner having a socket therein, a hub secured to said spindle and received within said socket, said hub being provided with a plurality of laterally projecting portions, means carried by said portions adapted to yieldably support said runner, and a plurality of driving arms on said hub and engaging said runner for imparting rotary movement thereto upon rotation of said spindle.

6. In combination, a vertical spindle, a runner having a socket therein, a hub secured to said spindle and received within said socket, said runner being provided with a plurality of portions depending within said socket, means carried by said hub for yieldably supporting said runner, and driving arms on said hub engaging the depending

portions of said runner for imparting rotary movement thereto upon rotation of said spindle.

7. In combination, a vertical spindle, a runner provided with an annular housing centrally thereof, a cover for said housing provided with a plurality of spaced lugs projecting downwardly therein, a plurality of arms formed on said hub, spring means carried upon said arms for yieldably supporting said runner, and a plurality of driving arms on said hub engaging the depending lugs on said housing cover for driving the runner upon rotation of said spindle.

8. In combination, a vertical spindle, a runner provided with an annular housing centrally thereof, a cover for the housing provided with a plurality of spaced lugs projecting downwardly therein, a hub secured to said spindle and received within said housing, a plurality of laterally projecting arms carried by said hub within the housing, compression springs resting upon said arms for yieldably supporting said runner, and a plurality of driving arms on said hub arranged alternately with said first named arms and being received between the downwardly projecting lugs and adapted to contact therewith to rotate the runner either in a clockwise or counter-clockwise direction upon rotation of said spindle.

9. In combination, a vertical spindle, a runner provided with an annular housing centrally thereof, a cover for the housing provided with a plurality of spaced lugs projecting downwardly therein, a hub secured to said spindle and received within said housing, a plurality of laterally projecting arms carried by said hub within the housing, compression springs resting upon said arms for yieldably supporting said runner, a plurality of driving arms on said hub arranged alternately with said first named arms and being received between the downwardly projecting lugs and adapted to contact therewith to rotate the runner either in a clockwise or counter-clockwise direction upon rotation of said spindle, and rolls carried by said driving arms and contacting with the inside of said housing.

10. In combination a vertical spindle, a runner formed with an annular housing centrally thereof, a hub secured to said spindle and received within said housing, said hub projecting upwardly beyond the housing and having an oil and the like receiving recess formed in the upper end thereof, a splash guard surrounding said recess, and a lower splash guard carried by said hub above said housing and surrounding the upper end of the latter.

11. In combination, a vertical spindle, a surfacing runner, a hub secured to said spindle, said hub being provided with a plurality of laterally projecting, substantially hori-

zontal portions, spring means supported upon said portions and yieldably supporting said runner thereupon, and a plurality of driving arms extending substantially horizontally from said hub and engaging said runner for imparting rotary movement thereto upon rotation of said spindle.

12. In combination, a vertical spindle, a surfacing runner provided with an annular housing centrally thereof, said housing being provided with a plurality of spaced lugs projecting downwardly therein, means carried by the hub within the housing for yieldably supporting the runner, and a plurality of driving arms on said hub engaging the depending lugs on said housing for driving the runner upon rotation of said spindle.

Signed at Pittsburgh, in the county of Allegheny and State of Pennsylvania, this 9th

20 day of July, 1927.
